UNITED STATES PATENT OFFICE

THOMAS SHAW, OF LANSING, MICHIGAN, ASSIGNOR TO ATLAS DROP FORGE CO., OF LANSING, MICHIGAN, A CORPORATION OF MICHIGAN

CRANK-TWISTING MACHINE

Application filed March 14, 1927. Serial No. 175,406.

This invention relates to a crank twisting machine, and has to do particularly with novel mechanism for gripping and twisting the various throws of multiple throw crank shafts of the type utilized in internal combustion engines.

In the forming of crank shafts with multiple throws positioned at various degrees of angularity it has been found expedient to forge the crank shaft with all the throws positioned in the same plane, and to subsequently twist the various throws to their proper angular positions. Heretofore in the twisting of crank shafts having the throws forged in the same plane, it has been customary to first clamp the shaft into position and then by subsequent operations to twist the various clamping members and then manually release the clamping members while in their twisted position in order to disengage the twisted shaft from the machine. It has heretofore been found necessary to restrike or retrim the forged and twisted crank shaft in order to accurately align and straighten up the various parts of the shaft. The machines of the prior art for accomplishing this twisting have heretofore been relatively heavy and somewhat cumbersome in operation in addition to requiring a relatively long time to perform the necessary operations and also, due to the design of the twisting apparatus, presented many small inaccuracies because of the wear of many of the necessary parts.

It is the object of the present invention to provide a compact and wholly automatic machine for gripping and automatically and positively positioning the forged shaft in a twisting block, twisting the various throws of the crank about fixed centers and automatically uncapping the twisting block in returning the same to position to present the twisted shaft complete without the necessity of restriking or reforming.

A further object of this invention has to do with the provision of novel mechanism for automatically and positively locking a twisting block and the caps therefor in various positions of operation whereby the crank is first positively clamped in the dies, each

part thereof being firmly pressed against the faces of the dies, the clamping and twisting block being positively locked until the operator can release the locking mechanism. By releasing the locking mechanism the twisting block is operated to twist the various throws into their final aligned positions at which time the various twisting blocks are again positively locked, making it impossible for the operator to attempt to return the twisting blocks to their normal position without unlocking the locking mechanism. The caps of the twisting blocks may then be released, the locking mechanism unlocked and the various uncapped twisting blocks returned to normal position with one automatic operation.

Another important feature of this invention resides in the provision of a crank twisting machine which is readily adjustable to accommodate crank shafts of various types, such as four-bearing and seven-bearing crank shafts and six and eight-throw crank shafts, the adjustments being attained by adjusting major parts of the machine only whereby such major parts operate about fixed spaced pivots or about fixed aligned pivots.

These and other novel features which will be brought out in the specification and claims are accomplished by a novel mechanism which includes a frame, to the bottom ends of which are pivoted two oppositely positioned but approximately axially pivoted cradles. These cradles are adapted to be oscillated by means of various links and levers, which links and levers are actuated by power means distributed by means of two shafts mounted longitudinally in the upper part of the frame. The various twisting blocks are connected directly or indirectly to these operably positioned cradles whereby the blocks are actuated by movement of the connected shafts to twist the various bearings and throws to their proper angular position about the centers fixed by the cradles. The positive and automatic clamping of the crank into place is accomplished by means of links positioned between the levers and the caps of the twisting blocks, while the automatic locking of the twisting

blocks before and after actuation is accomplished by locking mechanism attached to the cradles, and where four-bearing six-throw cranks are to be twisted by additional locking means connected to the members for twisting the end shaft bearings into position.

In the drawings:

Fig. 1 is an end elevation of a device embodying my invention and showing in particular the general arrangement of the frame, the positioning of the cradle members and the location and positioning of the shafts for carrying and operating the levers and links for actuating the twisting blocks and the cradles.

Fig. 2 is a cross sectional plan view taken on the line through the bearings for the cradles of Fig. 1, and illustrating in particular the positioning of a six-throw four-bearing crank shaft in the bottom dies of the respective twisting blocks, and also showing the manner of adjusting the twisting blocks for twisting the main front and rear bearings.

Fig. 3 is a vertical longitudinal sectional view taken on line 3-3 of Fig. 1 through the center of the bearings for supporting the main cradle, and illustrating the manner of supporting the cradles, and also illustrating the manner of pivoting the twisting block caps to the bottom of the twisting blocks, and the manner of connecting the twisting blocks to the cradles.

Fig. 4 is a detail view of the bearing block and linkage for twisting the front and rear main bearings of the four-bearing crank shaft, the twisting block being shown in its final twisted and locked position, the main end bearing having been drawn up into alignment with the center-shaft bearings. Attention is called to Fig. 1 which shows this twisting block in open position.

Fig. 5 is a detail view of the twisting block and the connecting levers for twisting the end crank bearings and the long cheeks, the normal position of the links being shown in dotted lines, and the position of the cheek and crank bearing being shown before and after twisting, in dotted lines.

Fig. 6 is a detail view of the locking mechanism for automatically locking the cradles at the ends of their path of movement.

Fig. 7 is a view similar to Fig. 6 which shows the locking mechanism from the reverse side, the cradle being moved to its opposite position.

Fig. 8 is a fragmentary detail view taken on line 8-8 of Fig. 3 and illustrating the clamping block for positively clamping and holding certain fixed cheeks and crank bearings in position during twisting, and illustrating the manner of moving the link past dead center to positively clamp the shaft into position.

Fig. 9 is a diagrammatic view illustrating the manner of twisting the long cheek and

crank center 30° about another crank center and then twisting the end cheek and end bearing 30° about the fixed crank center positioning the end bearing in axial alignment with the center shaft bearing.

Fig. 10 is a detail view of the central twisting block which is individually carried by one of the cradles, the twisting block being shown in closed position clamped against a portion of the crank shaft showing the locking link for positively clamping the cap of the twisting block into the crank shaft just before and after being in its locked position.

Fig. 11 is a cross sectional plan view, partially diagrammatic, and similar to Fig. 2, illustrating the adaptation of my device for the twisting of a seven-bearing six-throw crank shaft, the centers of the cradles being adjusted into axial alignment.

The preferred general structure of a frame for carrying and permitting operation of the various units going to make up my novel twisting apparatus, is best shown in Fig. 1 and may be generally designated 1. Most of the twisting apparatus is left off in this figure for the sake of clarity. The frame structure preferably comprises a base structure 2, as shown in Figs. 1 and 3, and suitable uprights 3 terminating in bosses 4 and 5 adapted to receive suitable shafts 6 and 7, which shafts 95 serve as main pivoting and power transmitting members.

The uprights 3 of the frame are connected at the top by suitable cross members 8 and a suitable bar (not shown) extends longitudinally and centrally between the two end frames and directly connected to cross members 8 at opposite ends of the general frame. Only one end frame is shown, of course, in Fig. 1, but the bottom parts of the two end frames are clearly shown in Fig. 2 and may be designated 9 and 10. The longitudinal top center bar for connecting the end frames is provided at points near the center thereof with two downwardly extending bosses 11, these bosses being adapted to serve as fulcrum and pivot points for operating levers for the fixed clamps, to be later described. It will be understood that the end frames at each end of the general frame structure are provided with suitable web sections between the upright and horizontal flanges, but for the purpose of clarity these end frames are assumed to be formed on the upright ends of vertical and horizontal flanges so as to show the various members in solid lines.

The bottom portion of each end frame 9 and 10 is provided with suitable journaled bearing members 12 and 13 which are adapted to be the main journals or trunnions of the twisting apparatus. These bearings are clearly shown in Figs. 2 and 3 and are adapted to receive suitable stub shafts 14 and 15 forming the supporting and pivoting means for a suitable cradle 16. This cradle

being best shown in Figs. 1, 2 and 3, Fig. 3 being taken on line 3—3 of Fig. 1 and looking in the direction of the arrows. The heavier sections of the end frames 9 and 10, as shown in Fig. 2, are adapted to adjustably support suitable members 17 and 18, which are apertured as at 19 and 20, for receiving suitable stub shafts 21 and 22 which are secured to arms 23 of another cradle member 24, as clearly shown in Fig. 2. The members 17 and 18 are adjustable relative to the end frames 9 and 10 whereby the trunnions 21 and 22 may be adjusted relative to the main center defined by the trunnions 14 and 15, or may be adjusted to axially align with said main centers. It will therefore be obvious from Figs. 1, 2 and 3 that I have provided two oppositely disposed cradle members which are journaled at the extreme ends of the main frame and on trunnions which are either in axial alignment or in spaced alignment.

The cradle member 16 has secured thereto, as best shown in Figs. 2, 3 and 10, a suitable crank twisting member which may be designated 26. This crank twisting member comprises a suitable base member which is provided with a suitable arm 27 for rigidly securing the same to the cradle. The crank twisting member 26 is divided into two parts, one being the base member 27 and the other being the cap 28, which is pivoted as at 29 to the base member. The cap 28 is preferably formed as the upper part of a die for clamping and twisting a certain part of the crank shaft, while the base member 27 is preferably provided with suitable tapered grooves and filler blocks for receiving the separate bottom part of the die 30. A clamping and twisting lever 31 is pivoted, as at 32, to the base member 27 and preferably directly below the twisting center of the twisting member, and the other end of this lever 31 is pivotally connected by means of a link 33 to the cap 28. The base member 27 is preferably formed of two spaced brackets or arms, as shown in Figs. 2 and 3, and the lever 31 is adapted to move between the spaced arms 27, as is well illustrated in Figs. 1 and 10, the arm 31 in Fig. 1 being in its downward position while in Fig. 10 being approximately in its clamping position. The lever 31 is adapted to be actuated by a suitable link 34 connected by means of a lever 35 directly to the shaft 7 and keyed thereto. It will be obvious from Figs. 1 and 10 that when the lever 31 is in its down position that the cap 28 will be swung upwardly from the lower die member 30. As the lever 31 is moved upwardly the cap 28 will be closed, as shown in Fig. 10, without movement of the cradle 16 which is at this time locked, as will be later described. Continued upward movement of the arm 31 will force the link 33 past or at its dead center to positively force the cap 28 into clamp-

ing position, and thus positively forcing the crank shaft into its position in the die. The lever 31 at this time will have been oscillated to a point where it will strike the base member 27 whereby when the cradle is unlocked the continued movement of the lever 31 will serve to oscillate the entire twisting member together with the cradle 16, about the cradle trunnions which are in direct alignment with the bearing of the shaft about which the particular part of the crank is then being twisted.

It may be well at this time to describe the parts and operation of this device as adapted to a four-bearing six-throw crank shaft, and in Fig. 2 I have illustrated such a crank shaft in position in the lower die members of the respective twisting members. Numbering the bearings and cheeks in order from the center outward the center crank bearings may be designated A, the adjacent cheek members of the bearings B, and the center shaft bearings C. The next cheek member may be designated D, the adjacent crank bearing E, and the long cheek member F. The end crank bearings may be designated G, the end cheek member H, and the end shaft bearings J. It will be understood that this crank shaft is forged flat with the bearings and cheek members in the same plane, as indicated in Figs. 2 and 3, and that certain of the parts of the crank are to be held stationary while other parts are to be twisted. As above described, the bearing member 27 and the cradle 16 are adapted to be oscillated about the trunnions 14 and 15, which are in alignment with the shaft bearings C whereby the cheeks B and the crank bearings A are twisted to an angle of 60°.

In the operation of my device the cheek member D and the crank bearing E are adapted to be held stationary and to this end I have provided suitable standards 37 which are rigidly secured to the base of the frame 2, and which rigid standards carry a suitable bottom die 38 and cap member 39, which cap member and die are adapted to clamp the cheek member D whereby the cheek B may be oscillated about the shaft bearing C, and the cheek member F about the crank bearing E. The cap member 39 is connected by means of a suitable locking link 40 to a link 41 which is adapted to be connected directly to the bearing member 11, shown in Fig. 1, and a suitable link and lever (not shown) freely connect this link 41 with the main shaft 6, a main lever being provided for oscillating the link 41 about the bearings 11. It will be obvious that if the link 41 is moved to the left, as viewed in Fig. 8, that the link 40 will be unlocked and the cap 39 raised to permit removal of the crank; while if the link 41 is moved to the right, the link 40 will be moved to upright locking position, as shown,

and parts of the shaft firmly forced into position.

The long cheek member F and crank bearing G are adapted to be twisted by means of a twisting member 43 quite similar to the twisting member 27. This twisting member 43 is pivotally connected to the cradle 24 by means of an arm 44 which forms also the base member for receiving the bottom part of the twisting die. The base member 44 is provided with a suitable bearing for pivotally carrying the cap 45. A lever 46 and link 47 are pivotally connected to the base 44 and the cap 45 similar to the connection described with reference to the twisting member 27. A suitable link 48 serves as a connecting means between the lever 46 and the lever 49 keyed to the shaft 6. The cradle member 24 is pivoted about the trunnions 21 and 22 in direct axial alignment with the crank bearings E, and it will be obvious that upon actuation of the lever 49 that the lever 46 will be initially moved to close the cap 45 and move the link 47 past or at dead center to lock the same in position, and continued movement of the lever 46 will move the entire twisting member 43 together with the cradle 24 about the centers 21 and 22 to twist the cheeks F 30° about the centers formed by the crank bearings E. It will be understood that this twisting of the cheek F and the bearing G will bring the crank bearing G at an angle of 60° from the main center of the crank shaft, as will be clearly obvious from Fig. 5.

The twisting of the cheeks H and the main end shaft bearings is accomplished by means of the structure best illustrated in Fig. 4. The twisting member may be designated 50, and instead of being rigidly connected to the cradle 24, it is slidably and pivotally connected to the arms 23 of said cradle. The partially diagrammatic view shown in Fig. 4 is preferably taken at the upper end of the frame, as viewed from Fig. 2, but it will be seen that such twisting member 50 comprises suitable arms 51 which provide a suitable extension and bearing member 52 for engaging the arms 23 of the cradle 24. These arms 23 are provided with a suitable slidable member 53 carrying suitable pins 54 and 55, the pin 54 being adapted to pivotally support the twisting member 50 about the point 54 which is in alignment with the shaft bearing G after it has been twisted to the position shown in Fig. 5. The pin 55 is adapted to engage a suitable slot 56 formed in the twisting member 50. The twisting member 50 is adapted to slidably engage the bearing member 43 and to be guided thereby by a suitable pin and slot connection 58, the slot being preferably wider than the pin to permit relative adjustment between the two twisting members. The member 53 for carrying the pins 54 and 55 is adjustable in the arm 23 whereby the machine

will accommodate cranks having throws of varying radius. It will thus be seen that the movement of the cradle 24 by means of the lever 49 will cause movement of the twisting member 50 by reason of the pin 55 engaging the top part of the slot 56 regardless of any movement of the twisting member 50 of itself. The twisting member 50 will then be capable of twisting the cheek H and bearing J downwardly about the center formed by the bearing E. In addition to this, however, the twisting member 50 is provided with a lever 60 which is connected to the cap 61 in the manner heretofore described, and this lever 60 is connected by means of suitable links 62, 63, and 64 to a lever 65 rigidly secured to the shaft 7. The shaft 7 is connected by means of the lever 66 (see Fig. 1), the link 67 and lever 68 to the shaft 6 whereby movement of the shaft 6 will move the shaft 7 and by its connected linkage move the levers 60 (see Fig. 4) and 27 (see Fig. 10) 60° about the centers of and on the cradles. It will thus be obvious that upon movement of the shafts 6 and 7 that the levers 60 will move the twisting members 50 sixty degrees, or thirty degrees in addition to the movement of the twisting member 43. By referring to Fig. 9, the action of the two twisting members 43 and 50 will be more clearly obvious, the twisting member 43 serving to twist cheek F 30° about the center E, and the twisting member 50, disregarding the lever 60, serving to twist the cheek H and center J in alignment with the cheek F. However, by bringing in the action of the lever 60 and the pivoting of the twisting member 50 about the pin 54, which is in alignment with the bearing G, it will be obvious that the cheek H and center J will be twisted 30° further or up into alignment with the main shaft of the crank.

The actuation of all the twisting devices is accomplished by means of a single actuating lever 70 which may be connected to any suitable source of power. The rigid or stationary clamping members 37 on either side of the center twisting member 27 are preferably closed by means of a lever fulcrumed on the shaft 6 connected to lever fulcrumed on a shaft in the bearings 11. This stationary clamp actuating lever may be automatically actuated simultaneously with the lever 70, or before or after actuation of such lever 70.

As best shown in Figs. 6 and 7, suitable locking devices 75 are mounted on the base 2 of the frame and so positioned as to engage the cradles 16 and 24. The figures show a front and rear view of the locking devices as connected to the cradle 16, but it will be understood that a similar device is secured to the opposite cradle 24. This locking device 75 consists of a standard slotted as at 76 to receive an adjustable member 77 through which extends a shaft 78. To one end of

this shaft is keyed a lever 79 pivotally connected to a link 80, which link is pivotally connected to the cradle members. The locking connection between the lever 79 and link 80 is by means of a suitable tapered joint 81 of such an angle whereby the lever 79 and link 80 are locked when they are in or past dead center alignment. The other end of the shaft 78 has secured thereto an arm 82 to which is connected a suitable piston 83 of a cylinder 84. Suitable actuation of this cylinder and piston 83 will actuate the shaft 78 to break the locking connection 81 whereby the cradle may be moved. It will thus be obvious, referring to Figs. 1, 6 and 7, that the cradle members 16 and 24 will be automatically locked whenever they assume their downward position or their upward position, as illustrated in dotted lines in Fig. 1. This locking of the cradles in downward or upward position may be broken by suitable actuation of the pistons 83. I have also provided suitable locking mechanism which may be generally designated 90, which consists of an arm secured to the cradle 24 at each end thereof, said arm having pivoted thereto a lever 91, and said lever being connected to the twisting member 50 by means of a link 92, a suitable locking connection 93 being provided between the lever 91 and link 92. As will be obvious from Figs. 1 and 4 this locking arrangement between the levers 91 and 92 will take effect when the cradle 24 and twisting member 50 are in their uppermost positions, or when they are in their lowermost positions, and such locking connections may be broken by means of a suitable link 94 connected at any position convenient to the operator.

In operation the caps of all the twisting members and the two stationary members are open, as shown in Fig. 1, at which time a suitable crank shaft may be placed in the bottom dies as shown in Fig. 2. Suitable actuation of the main lever for moving the stationary clamping lever 41, and suitable actuation of the main lever 70 by hydraulic or other means will, as best illustrated in Figs. 8 and 10, move the stationary clamping caps 39 and the clamping caps of all the twisting members automatically into position without actuating either of the cradles. Continued movement of the main actuating lever will position the various links 33 and 40 etc. whereby they will assume a position at or past dead center to positively force all the caps into position and thus positively force the forged crank into position against the surfaces of the bottom dies. The cradles 16 and 24 being in their lowermost position, as shown in Fig. 1, will be locked against movement by the locking devices 75, the same being true of the levers 60. The operator will thus be prevented from twisting the crank until all the caps have been securely forced into posi-

tion. Pressure of a suitable lever or operating means will then release the locking mechanism whereby the various levers 31, 60, etc., are further moved to actuate the twisting member and to simultaneously carry along the cradles 16 and 24 whereby the various twisting members will oscillate about the centers as heretofore described. The bearings C will remain stationary, the bearings A and cheeks B will be twisted 60° upwardly, the cheeks F and bearings G will be twisted 30° downwardly about the center E, and the cheeks H and end bearings J will then be twisted 30° upwardly, as illustrated in Fig. 9. After the twisting operation the cradles 16 and 24, as well as the twisting member 50, will be again locked in twisted position. The levers 70 may then be reversed as well as the lever for the stationary caps whereby all the caps may be moved upwardly while the lower part of the twisting members are in twisted position. The shaft may then be partially disengaged from the dies; the locking devices disengaged and the levers 70 continued in movement whereby the open caps and the bottom portions of the twisting members are all moved to normal horizontal and open position, at which time the shaft may be removed from the machine.

A further manner of operating my device is shown in Fig. 11 in which case the machine is adjusted to twist a seven-bearing six-throw crank shaft where all the throws and cheeks are equi-distant from the center. In this case the member 17 is adjusted until the bearing 21 is in alignment with the main bearing 15 whereby both cradles will operate about the same longitudinal axis. When the machine is adjusted to twist such a seven-bearing crank shaft it will be understood that the link 62 may be disengaged whereby the twisting member 50 will only operate through an arc of 30° and about the bearing 21. In such a condition the die members as well as the caps of the twisting members will be removed, the bottom die members being slid horizontally and other die members inserted, as shown in Fig. 11, whereby the various crank bearings may be twisted about the shaft bearings.

It will thus be obvious that I have provided a very simple and compact machine for twisting crank shafts, the major parts of which are adjustable to twist either a seven-bearing or four-bearing crank shaft. It will further be obvious that for twisting an eight-throw crank the center stationary clamps may be removed and each set of bearings may be twisted 90°.

What I claim is:

1. In a crank twisting machine, a crank twisting member comprising a block formed of a base and a cap pivoted thereto for clamping a portion of the crank into position preparatory to twisting, and means pivoted to

said cap and movable about a fulcrum on said base for closing the cap and actuating the twisting means.

2. In a crank twisting device for twisting cranks of multiple throw shafts, a twisting block for twisting certain bearings about fixed bearings, comprising a base and a cap for said base for clamping the shaft into place preparatory to twisting, and a single operative member pivotally connected to said base and said cap for positioning the cap on the base and oscillating said twisting block.

3. In a crank twisting device for twisting cranks of multiple throw shafts, a twisting block for twisting certain bearings about fixed bearings, comprising a base mounted to oscillate about an axis in alignment with said fixed bearing and a cap for said base for clamping the shaft into place preparatory to twisting, and a single means movable in a continuous operation to close said cap in the first part of its movement and actuate said block in the second part of its movement.

4. In a crank twisting device for twisting cranks of multiple throw shafts, a twisting block for twisting certain bearings about fixed bearings, comprising a base and a cap for said base for clamping the shaft into place preparatory to twisting, and means pivotally connected to said base and to said cap and movable in a continuous movement to close the cap, positively move it into lock clamping position, and actuate the entire block to twist a portion of the crank shaft.

5. A crank twisting device, comprising in combination a plurality of crank twisting members for gripping different parts of the crank, and twisting such parts about fixed bearings, and oppositely positioned and movable cradles one of which extends substantially the length of the crank and supports a plurality of twisting members, the ends of the cradles being mounted on centers in axial alignment with the axes of the respective fixed bearings.

6. A crank twisting device, comprising in combination a plurality of crank twisting members for gripping different parts of the crank, and twisting such parts about fixed bearings, oppositely positioned and movable cradles extending the length of and supporting the twisting members, the ends of the cradles being mounted on centers in axial alignment with the axes of the respective fixed bearings, and actuating means connected directly to said twisting members, said means being adapted to close the twisting members and clamp the crank in the first part of its movement, and to actuate the twisting members together with the cradles in the second part of its movement.

7. A crank twisting device, comprising in combination a plurality of crank twisting members for gripping different parts of the crank, and twisting such parts about fixed

bearings, oppositely positioned and movable cradles extending the length of and supporting the twisting members, and actuating means directly connected to said twisting members adapted in one part of its movement to positively close the twisting members to initially position the crank, and in another part of its movement to actuate the twisting members and the cradles about fixed centers.

8. A crank twisting device, comprising a plurality of twisting members positioned to receive the forged crank, oppositely positioned cradles pivoted beyond the ends of the twisting members and about fixed centers, the said twisting members being secured to said cradles, means for closing the twisting means about the crank to clamp the same into position preparatory to twisting, and means for locking said cradles and said twisting members whereby to positively prevent movement after said clamping of the crank until said locking means are released.

9. A crank twisting device, comprising a plurality of crank twisting members for twisting parts of the crank about certain intermediate bearings of the crank as centers, said members being supported and movable as units upon trunnions positioned in axial alignment with said intermediate bearing centers and independently of and beyond the ends of the crank.

10. A crank twisting device, comprising a plurality of crank twisting members for twisting parts of the crank about certain bearings of the crank as centers, said members being supported and movable as units upon trunnions in axial alignment with said bearing centers, one set of trunnions carrying twisting members rotatable about certain crank bearings and being adjustable to permit twisting of cranks having throws of a different radius.

11. In a crank twisting machine, a plurality of crank twisting members formed by pivotally connected upper and lower die members, and means connected to both die members and operable to close and then oscillate the closed die members in a plane at right angles to the axis of the crank being twisted.

12. A crank twisting machine comprising in combination a frame, a pair of cradles each pivotally mounted upon opposite ends of the frame and extending substantially the length of the crank, crank twisting members rigidly carried by said cradles for twisting parts of the crank, and twisting means pivotally carried by one of said cradles for twisting another part of the crank.

13. A crank twisting machine comprising a plurality of twisting members mounted to receive a crank having certain throws forged in the same plane and having crank bearings and shaft bearings, two of the twisting members being pivoted in axial alignment

with one crank bearing for twisting two cheeks connected by a crank bearing, and one of said two twisting members being pivoted in axial alignment with the crank bearing between said two cheeks for further twisting one of said cheeks and a shaft bearing on the end of the shaft.

14. A crank twisting machine comprising a plurality of twisting members for receiving and twisting certain parts of a crank shaft, caps for said members movable to force the crank into position, and means for locking said members against twisting movement until said caps have forced the crank into position, and means for locking said members in twisted position to insure opening of said caps before return of said twisting members.

15. A crank twisting machine comprising a frame having spaced end members, crank twisting members positioned between and pivoted centrally and at the bottom part of said end members, and two shafts mounted at the top of the frame, one serving to actuate the other, and means connecting said shafts with respective twisting members, whereby some members are twisted through greater angles than others.

16. In a crank twisting machine, a crank twisting member comprising a block formed of a base and a cap for clamping a portion of the crank into position preparatory to twisting, and means pivoted to the base of the block and below and centrally of said cap when in closed position for moving said cap into clamping position on said base.

17. A crank twisting machine for twisting cranks and multiple throw shafts, comprising in combination a twisting member formed of a base and a cap therefor, a cradle for rigidly supporting said base, and means pivotally carried by said cradle, and movable to position said cap in clamping position on said base, said means being pivotally connected to said cap at a point in alignment with said pivot between said means and said cradle.

18. A crank twisting machine, comprising in combination a plurality of crank twisting members movable to twist portions of the crank in opposite directions, a pair of cradle members also movable in opposite directions for carrying the respective twisting members, said cradle members being adjustable relative to each other whereby to adapt said twisting members to twist cranks for either equal-distant throws or non-equidistant throws.

19. In a crank twisting machine, a crank twisting member comprising a block formed of a base and a cap for clamping a portion of the crank into position preparatory to twisting, means connected to said cap and base for first closing the cap, and then actuating the complete twisting means, and means

for locking the twisting means against movement before actuation and after closing of said cap.

20. In a crank twisting machine, a crank twisting member comprising a block formed of a base and a cap for clamping a portion of the crank into position preparatory to twisting, means connected to said cap and base for first closing the cap, and then actuating the complete twisting means, and means for locking said twisting means before and after actuation.

21. In a crank twisting machine, a twisting member formed by pivotally connected upper and lower die members, and means pivotally connected to both die members, said pivotal connection between said means and said upper die member being by means of a link, said means being operable to close the twisting member and force the link at or past dead center to positively force the crank into the lower die member.

22. In a crank twisting machine, a twisting member formed by pivotally connected upper and lower die members, operating means connected to both die members for first closing the die members and then twisting the same by the same continued movement, the connection between the operating means and the upper die member being such as to close the twisting member and positively force the crank into the lower die member and to lock the same in such position during the twisting of the crank.

23. A crank twisting machine comprising a frame having spaced end members, crank twisting members positioned between and secured to cradles pivoted centrally of and at the bottom part of said end members, motion translating means mounted in the top of the frame, means connecting said motion translating means with respective twisting members and at a point whereby to first close and then twist the twisting members, and said motion translating means and connecting means being arranged whereby some members are twisted through greater angles than others.

24. In a crank twisting machine, a plurality of crank twisting members having lower die members and oppositely pivoted upper die members to permit insertion of the crank to be twisted, and means connected to both die members of the twisting members, the connection between said means and the upper die member being operable for first closing the upper die member and then positively forcing portions of the crank to their bottom position in the lower die members preparatory to twisting.

25. Crankshaft clamping and twisting mechanism comprising a pair of relatively separable cooperating elements one pivotally carried by the other, bearing means permitting unit rotation of said elements, and means

- automatically operating on said elements to first cause their relative movement to clamp a crankshaft throw and to second cause unit rotation of said elements to thereby twist said throw.
26. A crankshaft twisting machine comprising holding means for a crankshaft and twisting means for angularly swinging a throw of said crankshaft said means including a rotatable clamping twisting element, a cooperating clamping twisting element swingingly connected to the first said element, and power means acting to swing the last named element and subsequently to rotate the first named element with the second named element.
27. A crankshaft twisting machine comprising holding means for a crankshaft and twisting means for angularly swinging a throw of said crankshaft said means including a rotatable clamping twisting element, a cooperating clamping twisting element, a lever pivoted to the first element and connected to actuate the second element and power means acting on said lever to first move the second element into clamping relation with the first element and then to rotate both of said elements as a unit.
28. Crankshaft twisting mechanism including a first element, a second element, and connecting means for said elements permitting their combined rotation and relative movement toward or from each other, power means, means connecting the power means and said mechanism to rotate said elements together in opposite directions, said power means when acting in one direction serving to first move said elements relatively toward each other and then to rotate said elements together.
29. Crankshaft twisting mechanism including a first element, a second element, and connecting means for said elements permitting their combined rotation and relative movement toward or from each other, power means, means connecting the power means and said mechanism to rotate said elements together in opposite directions, said power means when acting in one direction serving to first move said elements relatively from each other and then to rotate said elements.
30. A crank twisting device, comprising crank twisting members for twisting parts of the crank about certain intermediate bearings of the crank as centers, said members being supported and movable as a unit upon trunnions positioned in axial alignment with said intermediate bearing centers and independently of and beyond the ends of the crank.
31. Crankshaft twisting mechanism including a first element, a second element, and connecting means for said elements permitting their combined rotation and relative movement toward or from each other, power means, means connecting the power means and said mechanism to rotate said elements together in opposite directions, said power means when acting in one direction serving to first move said elements relatively toward each other and then to rotate said elements together, said power means when acting in the opposite direction serving to first move said elements relatively from each other and then to rotate said elements.
32. In a crank twisting machine, a crank twisting device formed by pivotally connected upper and lower die members, and means connected to both die members and operable to close and then oscillate the closed die members in a plane at right angles to the axis of the crank being twisted.
33. A crank twisting machine for twisting cranks of the type having an end shaft bearing carried by an outer short cheek, two crank bearings connected by a single cheek, a short cheek and an inner shaft bearing out of alignment with said end shaft bearing, comprising a holding member for stationarily clamping the inner short cheek, a twisting unit mounted for rotation about a fixed axis for generally twisting said end shaft bearing, outer short cheek, crank bearing, and connecting cheek about the other crank bearing, and a member carried by said twisting unit having means for clamping said outer short cheek, said member being bodily movable relative to said twisting unit for positioning said end shaft bearing in alignment with the other shaft bearing.
34. A crank twisting machine for twisting cranks of the type having an end shaft bearing carried by a short cheek and two crank bearings directly connected by a relatively long cheek, comprising means for clamping the crank in such a manner as to hold the innermost of said crank bearings stationary, a main twisting unit mounted for rotation about a fixed axis and an auxiliary clamping twisting unit supported by the said main unit for clamping said short cheek to effect twisting of the end shaft bearing, said member being so supported by said unit as to be bodily movable relative thereto during part of the twisting action.
- In testimony whereof I affix my signature.
- THOMAS SHAW.
